J. NORTHROP.
LOOM TEMPLE THREAD CUTTER.
APPLICATION FILED JUNE 7, 1918.

Patented July 4, 1922.

Fig. 1

UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

LOOM-TEMPLE THREAD CUTTER.

1,421,815.

Specification of Letters Patent.

Patented July 4, 1922.

Application filed June 7, 1918. Serial No. 239,650.

To all whom it may concern:

Be it known that I, JONAS NORTHRUP, a citizen of the United States, residing at Hopedale, in the county of Worcester and State of Massachusetts, have invented certain new and useful Improvements in Loom-Temple Thread Cutters; and I do hereby declare the following to be a full, clear, and exact description of the invention, such as will enable others skilled in the art to which it appertains to make and use the same.

The present invention relates to an improvement in loom temple thread cutters.

The loom temple on the replenishing side of an automatic loom is usually provided with a thread cutter to sever immediately adjacent the selvage, the weft thread or strand of filling extending laterally from the selvage toward the weft replenishing mechanism. This strand of filling may be either the outgoing filling end, that is to say, the strand of filling which is left extending from the selvage to the shuttle by a critically exhausted filling carrier when the latter is ejected from the shuttle; or it may be the incoming filling end, that is to say, the strand of filling extending from the hopper stud to the selvage after the first pick of the shuttle following the replenishing operation. This filling or weft thread varies in quality and thickness according to the kind of fabric being woven; and it has been found that loom temple thread cutters which will successfully cut some kinds of filling will not successfully cut other kinds, especially the heavier kinds such as duck or canvas weft threads. It is accordingly one object of the present invention to produce a loom temple thread cutter of such construction and arrangement of parts that it will operate equally successfully in cutting both light and heavy weft threads. A further object of the invention is to produce a loom temple thread cutter of such construction that the positioning of the filling within the range of action of the cutting blades will be positively effected so that the filling will be severed at a particular time,—in the present instance on the beat-up of the lay following that on which the filling was beaten up against the fell. It is recognized of course that loom temples have heretofore been provided with thread cutters so constructed and timed in their mode of operation as to positively sever the filling at particular or predetermined

times; these thread cutters have also been constructed to successfully sever both light and heavy filling; but so far as is known at the present time, these loom temple thread cutters have been more or less complicated in construction and unenduring in use. The positively acting thread cutter of the present invention on the contrary is as simple in structure and as enduring in use as is the usual form of temple thread cutter, with this feature of advantage however, that it acts positively at a particular time to sever the filling and is capable of severing successfully all kinds of filling. The present invention consists in the improved loom temple thread cutter hereinafter described and particularly pointed out in the claims.

The preferred form of the invention is illustrated in the accompanying drawings in which Figure 1 is a side elevation of a loom temple showing the application thereto of the improved thread cutter of the present invention; Fig. 2 is a plan of the thread cutter and of the rear end of the temple; and Fig. 3 is a side elevation of the thread cutter showing the cutter blades in the position they assume when the lay is on its front center.

The loom temple to which the improved thread cutter of the present invention is shown as applied, comprises the temple rod 4 which carries at its rear end or head 5, the roll cover 6 and the heel 7 by which on the forward beat of the lay the temple rod is moved forward upon the rod guide 9 which is secured to the breast beam 10. The temple rod 4 is moved rearwardly by its usual internally arranged spring. The loom temple carries on its rear end the improved thread cutter of the present invention. The loom temple is located on the breast-beam in such a position as to bring the thread cutter immediately outside and adjacent to the selvage of the cloth.

The improved loom temple thread cutter 100 comprises two cooperating blades, an upper or oscillatory blade 14 and a lower or reciprocatory blade 15. The cutting part of the reciprocatory blade consists of two parallelly arranged members 16 and 17 (Fig. 102) which receive the oscillatory blade 14 between them and on which the oscillatory blade is pivoted at 18. The reciprocatory blade 15 is supported for sliding movements forwardly and rearwardly on a lug 20 which 110

projects laterally from a cutter support 21 secured by a bolt 22 to the loom temple head 5. The reciprocatory blade is held in place by a side cover 24 which is secured to the cutter support 21 by a screw 25. The reciprocatory cutter blade 15 is provided at its forward end with a downwardly projecting heel 27 which extends rearwardly slightly beyond the temple heel 7 into the path of travel of the lay. A spring 28, the upper end of which encircles a pin 29 projecting laterally from the cutter support 21 and the lower end of which encircles a pin 30 in the cutter heel 27, tends to press the reciprocatory blade rearwardly toward the lay as shown in Fig. 1. This position of the reciprocatory blade is its normal position and when it is in this position the rear end of the reciprocatory blade projects rearwardly beyond the fell of the cloth which is substantially on a line with the rear edge 31 of the temple head, or slightly to the rear thereof. The movement of the reciprocatory blade rearwardly toward the lay carries the cam part 32 of the oscillatory blade 14 against a roll 33 which turns on a pin 34 fixed in the upper part of the rear end of the cutter support 21. The engagement of the cam part 32 by the roll 33 causes the oscillatory blade to swing on the pivot pin 18 as the reciprocatory blade completes its rearward movement thereby opening the blades to receive the filling between them. A shoulder 35, formed on the lower forward end of the oscillatory blade, by its engagement with the upper surface of the reciprocatory blade determines the open position of the oscillatory blade. The rearward movement of the blades is limited by the engagement of a shoulder 38 formed on the cutter heel 27 with the lug 20 on the blade support. The reception of the filling between the blades is facilitated by the beveled rear edges 37 of the blades which act to direct the filling between the blades. When the filling is beaten up against the fell by the reed 40, it is held there by the crossing of the warp threads. While the reed is against the fell, the lay is on its front center and the cutter blades are in the position shown in Fig. 3. If now this filling is either the outgoing filling end or the incoming filling end, the part thereof extending laterally outwardly from the selvage will remain in the path of the cutter blades as they move rearwardly on the backward beat of the lay. The filling being engaged by the beveled edge 37 of either the reciprocatory or the oscillatory blade, will be directed toward the point of divergence 42 of the beveled edges of the blades. The pressure of the blades against the filling, as they move rearwardly with the filling before opening, puts it under a slight tension, so that when the blades open, the filling snaps forwardly again and between the opened blades. It is thus seen that as the blades move rearwardly closed, their rear edges engage the filling extending laterally outwardly from the selvage and direct it into position to be received between the blades when the blades open. Thus the action of the blades upon the filling is positive and certain.

It is apparent from the foregoing description of the construction of the improved loom temple thread cutter that the lay strikes the cutter heel 27 on each forward beat and thereby pushes the reciprocatory blade forward with it and that on the return or backward beat of the lay the spring 28 moves the blade rearwardly. As the reciprocatory blade moves forwardly under pressure of the lay it carries the oscillatory blade with it and this causes the upper surface 39 of the oscillatory blade to be drawn under the roll 33 so as to close the oscillatory blade upon the reciprocatory blade as shown in Fig. 3. The oscillatory blade is closed upon the reciprocatory blade before the blades reach the position shown in Fig. 3. In fact the oscillatory blade closes upon the reciprocatory blade immediately after the striking of the heel 27 by the lay. This is necessary in order that the filling may be acted upon before the blades are pushed forwardly beyond the fell. It will be apparent from a consideration of Fig. 3 that the blades can never act upon the filling on the beat-up during which the filling is beaten against the fell by the reed 40, because by the time the reed reaches the fell the blades have been closed and moved forward.

Let it be assumed for the purposes of illustration that the loom temple thread cutter of the present invention is applied to a feeler controlled replenishing loom and that the filling feeler mechanism has indicated that the filling in the active shuttle has been exhausted to a predetermined extent. Accordingly, on the replenishing beat-up of the lay, with the shuttle in the replenishing shuttle box, an intact strand of filling will extend from the selvage to the filling carrier about to be ejected. As before described, this filling will not be severed by the thread cutter on this beat-up of the lay. The replenishing operation having taken place and the usual feeler thread cutter and clamp having operated to sever and clamp the outgoing filling end relatively near the inner end of the replenishing shuttle box, the lay beats backward. As the lay moves from engagement with the heel 27 the spring 28 moves the cutter blades rearwardly and presses them against the filling, the beveled edges 37 directing the filling to the point of divergence 42 of the beveled edges. The outgoing filling end is now in a position to be received between the cutter blades as they open. This filling end being held at the fell

of course does not move rearwardly with the lay so that when on the next beat-up, the lay strikes the cutter heel 27 to move the blades forwardly, the blades close upon and

5 sever the filling end. During this beat-up of the lay, which is the first beat-up following the replenishing operation, the incoming filling end has been beaten up against the fell. It is accordingly in position to be received 10 between the cutter blades on the next backward beat of the lay, and is then severed on the next succeeding forward beat of the lay. It is thus seen that the outgoing filling end is severed by the thread cutter of the 15 present invention on the first forward beat of the lay after replenishment and that the incoming filling end is severed on the second forward beat of the lay after replenishment.

It will be observed that by reason of the 20 particular arrangement of the pivot pin of the oscillatory blade with respect to the roll 33, which by its engagement with the upper surface 39 of the oscillatory blade causes the blade to be closed upon the reciprocating 25 blade, a considerable leverage is exerted by the cutting end of the blades upon any substance that might be between the two blades, and that consequently it is possible for the blades to sever successfully the heaviest 30 kinds of filling. Another advantage of the present construction of thread cutter lies in the fact that the blades, by reason of extending rearwardly beyond the fell, are actuated to close upon the filling while the lay is yet 35 at a substantial distance from its forward center and at a time when the lay is moving comparatively rapidly. Consequently the impetus of the impact of the lay against the cutter heel 27 is such as to impart a rapid 40 closing movement to the oscillatory blade. This materially assists in causing the blades to perform successfully their cutting operation on the heaviest kinds of filling.

Having thus described the invention what 45 is claimed is:

1. A thread cutter for looms comprising a movable supporting member, cutter blades mounted thereon and capable of movement independently thereof, the cutter blades having 50 beveled rear edges adapted to engage a strand of filling when the cutter blades are moved rearwardly in a closed position and to thereby position the filling under tension to be received between the blades when they 55 are opened, and means for opening the blades at near the end of their rearward movement and for closing the blades at the beginning of their subsequent forward movement.

2. A thread cutter for looms comprising 60 a movable supporting member, cutter blades mounted thereon and capable of movement independently thereof, the cutter blades having beveled rear edges adapted to engage a strand of filling when the cutter blades 65 are moved rearwardly in a closed position

and to thereby position the filling under tension to be received between the blades when they are opened, and means for moving the blades.

3. A thread cutter for looms comprising 70 two movable cutter blades provided with beveled rear edges, which cooperate to form a filling engaging mouth when the blades are closed, means for moving the cutter blades in a closed position toward the lay to 75 engage a filling strand within the mouth and to place it under tension, means to open the blades after the filling strand has been engaged to permit it to snap between the blades, and means to close the blades and 80 sever the thread upon movement of the blades in the other direction.

4. A thread cutter for looms comprising cutter blades movable forwardly and rearwardly, means for moving said blades forwardly and rearwardly, and means for opening and closing the blades having provision whereby the blades are presented in a closed 85 position to an outgoing filling thread on the replenishing beat up of the lay, are opened to 90 receive the filling thread on the next backward beat of the lay, and are closed to sever the thread on the first beat up of the lay after replenishment.

5. A thread cutter for looms comprising 95 cutter blades movable forwardly and rearwardly, means for moving said blades forwardly and rearwardly, and means for opening and closing the blades having provision whereby the blades are presented in a closed 100 position to an incoming filling thread on the first beat up of the lay after replenishment, are opened to receive the filling thread on the next backward beat of the lay, and are 105 closed to sever the thread on the second beat up of the lay after replenishment.

6. A thread cutter for looms comprising cutter blades movable forwardly and rearwardly, means cooperating with the latter to present the blades in a closed position to 110 an outgoing filling thread on the replenishing beat up of the lay, to open the blades and receive the outgoing filling thread on the next backward beat of the lay, to close the 115 blades and sever the outgoing filling thread on the first beat up of the lay after replenishment, and at the same time to present them in closed position to the incoming filling thread on the next backward beat of the lay and to close the blades and sever the incoming filling thread on the second beat 120 up of the lay after replenishment.

7. A thread cutter for looms comprising cutter blades movable forwardly and rearwardly, and means for opening and closing 125 the cutter blades, said means having provision whereby the cutter blades engage, in a closed position as the lay beats forward, a filling end extended from the selvage other than the filling end leading to the active 130

shuttle, are opened to receive the filling on the next backward beat of the lay, and are closed to sever the filling on the next forward beat of the lay.

5 8. A thread cutter for looms comprising cutter blades movable forwardly and rearwardly, and means for opening and closing the cutter blades, said means having pro-

vision whereby the blades are closed before engaging a filling thread extended from the selvage other than the filling thread leading to the active shuttle, so that the thread thus engaged is never severed on the beat up of the lay upon which the particular filling is beaten against the fell.

JONAS NORTHRUP
